BELT CONVEYER

Walter Jacob Mann, Plainfield, N. J., assignor to
General Conveyors Limited, Montreal, Quebec,
Canada, a corporation of Canada

Application February 2, 1931, Serial No. 512,914
Renewed June 21, 1932

38 Claims. (Cl. 198—160)

Important objects of the present invention are, to provide an improved belt conveyer of the drag type for conveying message sheets such as telegrams and the like; to provide such a conveyer designed for more rapid and safe conveyance of the sheets; to provide such a conveyer with means for obtaining good frictional holding engagement of the sheets with the belts, so that the sheets will be conveyed more positively and rapidly; to prevent the sheets from wrapping around the belts with the consequent possibilities of tearing and failure to detach at the delivery point; to provide a drag belt conveyer having cooperating twin belts and means for holding the conveyed sheets flexed between the belts for good holding engagement with them; to provide for the feeding of sheets to a drag belt conveyer at intermediate points along a belt reach; and to provide a drag belt conveyer designed to operate satisfactorily in inverted position with the conveyer faces of the belts directed upward so that the sheets may be fed downward upon intermediate points of the belt reaches. Other objects of the invention will appear hereinafter.

In the drawings, Fig. 1 is a side view, partly in section, of a conveyer system embodying my invention;

Fig. 2 an enlarged detail section taken on the line 2—2 of Fig. 1;

Fig. 3 an enlarged horizontal section taken on the line 3—3 of Fig. 1, with parts broken away;

Fig. 4 an enlarged vertical section taken on the line 4—4 of Fig. 1;

Fig. 5 an enlarged horizontal section taken on the line 5—5 of Fig. 1;

Fig. 6 a section taken on the line 6—6 of Fig. 3;

Fig. 7 a detail sectional view of a modified form of sheet-guiding track plate;

Fig. 8 a detail sectional view of another modified form of sheet-guiding track plate;

Fig. 9 a side view partly in section of another form of conveyor system embodying my invention;

Fig. 10 an enlarged detail section taken on the line 10—10 of Fig. 9;

Fig. 11 a detail section taken through one of the feed hoppers of the system;

Fig. 12 a section taken on the line 12—12 of Fig. 11; and

Fig. 13 an enlarged detail section taken on the line 13—13 of Fig. 9.

The belt conveyer system shown in Fig. 1 includes a skeleton frame structure supporting the pulleys and belts and comprising a pair of spaced columns 1 and 2 and a horizontal frame 3 con-

necting them. Column 1 is formed of four vertical rods 4 having their ends detachably secured in sockets formed upon plates 5 and 6 secured to the floor and ceiling respectively. Column 2 is similarly formed of four rods 7 having their upper ends detachably secured in sockets formed upon a plate 8 secured to the ceiling. The lower ends of rods 7 are detachably secured to a similar plate 9 mounted upon the top of a frame 10. This frame defines an elevated receptacle 11 for sheets 10 discharged from the conveyer, and an enclosure 12 beneath said receptacle for the conveyer driving motor 13. Said receptacle and enclosure preferably have perforated or grille-like walls. The horizontal frame 3 connecting the columns 15 is disposed beneath the ceiling and comprises four rods 14 whose ends are detachably fastened in sockets formed upon coupling members 15. Said members are formed with inwardly opening hooks which engage two of the column rods and 20 are detachably secured to them by set screws 16. Intermediate hanger rods 17 are detachably secured to the ceiling and bear hooks 18 which engage the rods 14 and have set screws engaging the latter.

Attached to column 1 at intermediate points thereof are two pairs of transverse stiffening and shaft-supporting bars 19 and 20. Each bar has inwardly opening hooks 20' at its ends which engage the column rods and have set screws 21 readily fastening them in place. Each bar has a shaft bearing socket 22. Three pairs of similar bars 23, 24 and 25 are mounted upon column 2 and similarly secured. The bearings of bars 19 support a shaft 19' upon which two belt pulleys 35 26 are rotatably mounted in slightly spaced relation. Bars 20 support, in their bearings, a shaft 27 upon which two pulleys 28 are rotatably mounted. A shaft 29 is supported in the bearings of bars 23 and has a pair of belt pulleys 30 30 fixed upon it. Another shaft 31 is supported in the bearings of bars 24, and rotatably bears two spaced pulleys 32. Still another shaft 33 is supported by the bars 25 and has a pair of pulleys 34 rotatably mounted upon it. All of these shafts 34 are held to the bars by set screws 34' and the pulleys are held spaced apart by collars fixed to the shafts.

The frame structure also supports a number of belt pulleys 35, 36, 37 and 38 rotatably mounted 50 in pairs upon shafts, and each shaft is supported by a pair of bearing brackets 39. Each of said brackets has a hook-like end which engages one of the frame rods and is detachably clamped to it by a set screw. All of these pulleys are held 55

side by side, guide the discharged sheets into an open side of the receptacle 11.

The twin belts of my conveyer system cover the conveyed sheets in a manner to prevent material marginal exposure of the sheets, and thereby prevent the sheets from wrapping around the belts, failing to detach at the discharge point and tearing at the pulleys, all of which frequently occurs in single belt systems. The important feature of the central plate ridge holds the dragged sheets flexed in a manner to obtain a good dragging hold to the belts and positively prevent lateral displacement of the sheets beneath the belts. Thereby the sheets may be conveyed at a greatly increased speed and with entire safety.

Fig. 7 shows a modified form of my sheet-retaining track plate. In this plate, designated 82, the side ridges are omitted and the longitudinal edges are merely curled beneath the plate as at 83 to stiffen it. Otherwise the plate is the same as that previously described, having the central ridge 84 and the twin belt tracks. This form of the track plate affords lateral clearance along the outer edges of the tracks for lateral entry to the tracks to clean them. Drag belts often pick up much dirt and deposit it on the belt tracks where it increases the frictional resistance to the travel of the belts and the conveyed sheets. The track plate shown in Fig. 7 is free of obstructions along its outer edges so that a cloth can be readily inserted beneath the belts to wipe off the tracks.

Another form of the sheet-retaining track plate is shown in Fig. 8. Here, the plate, designated 85 is formed with two medially disposed, parallel, longitudinal ridges 86 instead of a single central ridge. The belt tracks 87 are disposed outward of said ridges and the conveyed sheets are flexed across the space between the ridges. This track will accommodate three belts if desired and the belts will hold the sheet in contact with the crests of the ridges 86 and flexed thereover along the parallel medial lines.

Figs. 9 to 13 inclusive show another form of conveyer system embodying my invention. Here an inverted form of drag conveyer is employed in a portion of the system to provide for the feeding of sheets at a number of intermediate points along the conveyer line. In the system there is a pair of companion endless drag belts 88 which are trained in succession over a pair of pulleys 89, a pair of pulleys 90 at the same level as pulleys 89, a pair of pulleys 91 at a lower level and a still lower pair of pulleys 92, and back over pairs of pulleys 93, 94 and 95. Between the pulleys 93 and 94 the return reaches of the belts are trained over a pair of tensioning pulleys 96. The latter are mounted upon a shaft which is weighted at 97, and supported by swinging arms 98. The belts are driven in unison by a motor 99 which has a driving connection 100 with the shaft of pulleys 92. Between the upper pulleys 89 and 90 the horizontal belt reaches form a feed-line and have their conveyer faces directed upward. At their under faces said belt reaches are supported horizontal by flat track rails 101 over which they are dragged. Transverse bars 102 support said rails and are in turn supported by parallel angle irons 103. The showing of the system is diagrammatic and the supporting means for the angle irons and for a number of the pulleys of the system have been omitted.

Overlying the upwardly directed conveyer faces of the horizontal belt reaches is a longi-

tudinal series of sheet retaining and guiding plate sections 104 similar in cross section to the plate shown in Fig. 7 but inverted. These plate sections are supported slightly spaced above the belt faces by hopper structures 105 located at spaced points along the feed line. Each of said structures comprises a casting forming a yoke 106 and an upwardly flaring hopper, opening downward through the yoke. The yoke straddles the angle irons 103 and is adjustably secured to them by bolts 107 which are passed through vertical slots 108 in the legs of the yoke. The ends of the plate sections 104 are riveted or otherwise secured to the under sides of the yokes of the different hoppers, so that by vertically adjusting the yoke the plate sections may be accurately positioned in proper spaced relation to the belt faces. Since the plate sections are inverted, their central ridges 104a project downward between the belts. Sheets fed into the hoppers drop upon the belts, are pulled thereby beneath the plates and are dragged along the latter. An inclined ridge 109 at the bottom of each hopper merges the hopper exit with the ridge 104a and guides the inserted sheets over the latter. The ridge 104a flexes or crimps the sheets into holding engagement with the belts and holds them against lateral displacement.

The endmost plate section 104 is elongated and extends over the pulleys 90 and downward as at 104b along the descending belt reaches to a point near the pulleys 92. The descending portion of said plate is in direct contact with the belts, as shown in Fig. 13, and cooperates therewith as described in the preceding system. It may be supported in any suitable manner and may also be in sections instead of continuous. At its lower end it is bent downward to direct the discharged sheets upon a pick-up belt 110. Stripper prongs 111 disposed at an angle to the belts serve to positively strip the sheets from the belts at the discharge point.

What I claim is:

1. In a drag belt conveyer system, a pair of parallel belt tracks disposed side by side; a pair of transversely spaced, companion drag belts trained to slide along said tracks and drag an interposed sheet along both tracks with the medial portion of the sheet bridging the space between the belts; and means between the belts and extending along them to engage the medial portion of the sheet and hold it flexed to prevent lateral displacement of the sheet and maintain it in frictional holding engagement with the belts for positive conveyance along the tracks.

2. In a belt system for conveying sheets, a pair of transversely spaced, companion conveyer belts trained to run side by side; track means extending along said belts and opposed to their conveying faces to hold an interposed sheet to said faces of both belts with the medial portion of the sheet bridging the space between the belts; and means between the belts and extending therealong to engage the medial portion of the sheet and hold it flexed to prevent lateral displacement of the sheet and maintain it in frictional holding engagement with the belts.

3. In a drag belt conveyer system, a pair of parallel belt tracks disposed side by side; a pair of transversely spaced, companion drag belts trained to slide along said tracks and drag an interposed sheet along both tracks with the medial portion of the sheet bridging the space between the belts; and a ridge between the belts and extending longitudinally thereof to engage the medial portion

of the sheet and hold it flexed as the sheet is dragged.

4. In a belt conveyer system for conveying sheets, a pair of transversely spaced, companion conveyer belts trained to run side by side; sheet guiding and retaining means extending along said belts and opposed to their conveyer faces to hold an interposed sheet to said faces of both belts with the medial portion of the sheet bridging the space between the belts; and a ridge between the belts and extending longitudinally thereof to engage the medial portion of the sheet and hold it flexed as the sheet is conveyed.

5. In a belt conveyer system for conveying sheets, a pair of transversely spaced, companion conveyer belts trained to run side by side; sheet guiding and retaining means extending along said belts and opposed to their conveyer faces to hold an interposed sheet to said faces of both belts with the medial portion of the sheet bridging the space between the belts; and a ridge between the belts and extending longitudinally thereof to engage the medial portion of the sheet and hold it flexed as the sheet is conveyed, the crest of said ridge being inclined at one end for flexing the sheet and guiding it into conveying position.

6. In a drag belt conveyer system, a pair of parallel belt tracks disposed side by side; a pair of transversely spaced, companion drag belts trained to slide along said tracks and drag an interposed sheet along the tracks with the medial portion of the sheet bridging the space between the belts; means between the belts and extending therealong to engage the medial portion of the sheet and hold it flexed for holding engagement with the belts and positive conveyance along the tracks; and means for adjusting the tracks toward and from the belts.

7. In a belt conveyer system for conveying sheets, a pair of transversely spaced, companion conveyer belts trained to run side by side; a track plate extending along said belts and opposed to their conveyer faces to hold an interposed sheet to both of said faces with the medial portion of the sheet bridging the space between the belts; and a ridge carried by the track plate between the belts and extending therealong to hold the sheet flexed for holding engagement with the belts.

8. In a belt conveyer system for conveying sheets, a pair of transversely spaced, companion conveyer belts trained to run side by side; track means extending along said belts and opposed to their conveyer faces to hold an interposed sheet to said faces of both belts, with the medial portion of the sheet bridging the space between the belts; means between the belts and extending therealong to engage the medial portion of the sheet and hold it flexed for holding engagement with the belts and positive conveyance along the track means; and means for adjusting the track means toward and from the belts.

9. In a drag belt conveyer system, a pair of parallel, slightly flexible belt tracks disposed side by side; a pair of transversely spaced, companion drag belts trained to travel along said tracks and drag an interposed sheet along both tracks with the medial portion of the sheet bridging the space between the belts; a ridge between the belts and extending therealong to outwardly flex the sheet for holding engagement with the belts; and adjustable means for bowing the flexible tracks for close engagement with the belts.

10. In a belt conveyer system for conveying sheets, a pair of companion conveyer belts trained to run side by side in transversely spaced rela-

tion; a sheet metal track plate extending along said belts and opposed to their conveyer faces to hold an interposed sheet to both of said faces, the track plate being bent outward along a longitudinal medial line to form a ridge projecting between the belts to hold the sheet flexed as it is conveyed.

11. In a belt conveyer system for conveying sheets, a pair of companion conveyer belts trained to run side by side in transversely spaced relation; a track plate extending along said belts and opposed to their conveyer faces to hold an interposed sheet to both of said faces, the track plate having a pair of parallel ridges extending therealong between the belts to hold the sheet flexed outward for holding engagement with the belts.

12. In a drag belt conveyer system, a sheet metal plate bent along parallel marginal and medial lines to define a pair of parallel channels and a longitudinal ridge between said channels; and a pair of companion drag belts trained to run within said channels and drag a sheet therealong, with the sheet interposed between both belts and channels and its medial portion extending across said ridge, the ridge serving to hold the sheet flexed outward for holding engagement with the belts.

13. In a drag belt conveyer system, a sheet metal plate bent along parallel marginal and medial lines to define a pair of parallel channels and a longitudinal ridge between said channels; and a pair of companion drag belts trained to run within said channels and drag a sheet therealong, with the sheet interposed between both belts and channels and its medial portion extending across said ridge, the ridge serving to hold the sheet flexed outward for holding engagement with the belts, and the crest of the ridge and the outer sides of the channels being inclined at one end for flexing the sheet and guiding it into conveying position.

14. A belt conveyer line for conveying sheets comprising a pair of transversely spaced companion belt reaches trained to run side by side with their conveyer faces directed upward; sheet guiding and retaining means overlying and extending along said belt reaches and opposed to their conveyer faces to hold an interposed sheet disposed between both belts and the guiding and retaining means; supporting means engaging the under faces of said belt reaches and supporting them in fixed relation to the sheet retaining means; and a ridge projecting downward below said sheet-retaining means and between the belts and extending therealong to flex the sheet, the sheet-retaining means and ridge having a gap at an intermediate point in the line for the insertion of sheets into conveying position between the retaining means and the belts.

15. A belt conveyer line for conveying sheets comprising a pair of transversely spaced companion belt reaches trained to run side by side with their conveyer faces directed upward; sheet guiding and retaining means overlying and extending along said belt reaches and opposed to their conveyer faces to hold an interposed sheet disposed between both belts and the guiding and retaining means; supporting means engaging the under faces of said belt reaches and supporting them in fixed relation to the sheet retaining means; and a ridge projecting downward below said sheet-retaining means and between the belts and extending therealong to flex the sheet, the sheet-retaining means and ridge having a gap at an intermediate point in the line for the insertion of sheets into conveying position between the retaining means and the belts.

sertion of sheets into conveying position between the retaining means and the belts, and the ridge having a tapered portion leading from said gap to the peak of the ridge for flexing the sheets and 5 guiding them into conveying position.

16. A belt conveyer line for conveying sheets comprising a pair of transversely spaced companion belt reaches trained to run side by side with their conveyer faces directed upward; sheet 10 guiding and retaining means overlying and extending along said belt reaches and opposed to their conveyer faces to hold an interposed sheet disposed between both belts and the guiding and retaining means; supporting means engaging the 15 under faces of said belt reaches and supporting them in fixed relation to said sheet retaining means; and a ridge projecting downward below the sheet-retaining means and between the belts and extending therealong to hold the sheet flexed. 20

17. A belt conveyer line for conveying sheets comprising a pair of transversely spaced companion belt reaches trained to run side by side with their conveyer faces directed upward; sheet 25 guiding and retaining means overlying and extending along said belt reaches and opposed to their conveyer faces to hold an interposed sheet disposed between both belts and the guiding and retaining means; supporting means engaging the under faces of said belt reaches and supporting them in fixed relation to the sheet retaining means; a ridge projecting downward below said sheet-retaining means and between the belts and extending therealong to hold the sheet flexed; the sheet-retaining means having a gap 30 at an intermediate point in the line for the insertion of sheets into conveying position between the retaining means and the belts; and means for relatively adjusting the sheet-retaining means and said belt-supporting means toward 35 and from each other to vary the space between the conveying faces of the belt reaches and the sheet-retaining means.

18. A belt conveyer line for conveying sheets comprising a pair of transversely spaced conveyer 40 belt reaches trained to run side by side with their conveyer faces directed upward; sheet guiding and retaining means overlying and extending along said belt reaches and opposed to their conveyer faces to hold an interposed sheet 45 disposed between both belts and the guiding and retaining means; supporting tracks engaging the under faces of the said belt reaches and supporting them for dragging therealong in fixed relation to the sheet retaining means; and a 50 ridge projecting downward below said sheet retaining means and between the belts and extending therealong to hold the sheet flexed; the sheet-retaining means and ridge having a gap 55 at an intermediate point in the line for the insertion of sheets into conveying position between the retaining means and the belts.

19. In a belt conveyer system, a pair of companion conveyer belts trained to form a pair of transversely spaced conveyer belt reaches 60 trained to run side by side with their conveyer faces directed upward, and a pair of transversely spaced, side by side conveyer belt reaches continuing from said first reaches and trained to extend therefrom at an angle and lead to an 65 other elevation; sheet guiding and retaining means overlying and extending along the conveyer faces of both pairs of belt reaches to hold an interposed sheet for conveyance by both belts, said retaining means having a feed gap at an intermediate point in the length of the first reaches 70

for the insertion of sheets into conveying position between the retaining means and the belts; and a ridge extending along the sheet-retaining means and projecting inward between the belt reaches for holding the conveyed sheets flexed. 5

20. In a drag belt conveyer system for conveying sheets, a pair of spaced co-axial belt pulleys; a pair of transversely spaced drag belt tracks extending from a point adjacent the peripheries of said pulleys; a pair of drag belts trained over the pulleys and along said tracks with their conveyer faces opposed to the pulleys and tracks, for conveying a sheet around the pulley and dragging it along the tracks; a ridge between the tracks extending therealong, projecting outward 10 between the belts for flexing the sheet and extending at one end longitudinally beyond the tracks and inclining inward between the pulleys 15 to flex the sheet and guide it from the pulleys to the tracks. 20

21. In a drag belt conveyer system for conveying sheets, a pair of transversely spaced, companion conveyer belts trained to run side by side; sheet guiding and retaining means extending along said belts and opposed to their conveyer 25 faces to hold an interposed sheet to said faces of both belts with a medial portion of the sheet bridging the space between the belts; and means to flex said medial portion of the sheet out of the plane of the belts. 30

22. In a drag belt conveyer system for conveying sheets, a pair of transversely spaced, companion conveyer belts trained to run side by side; sheet 35 guiding and retaining means extending along said belts and opposed to the conveyer faces thereof to hold an interposed sheet to said faces of both belts with a medial portion of the sheet bridging the space between the belts; and a sheet-flexing projection disposed between the belts to flex said medial portion of the sheet out 40 of the plane of the belts. 40

23. A belt conveyer line for conveying sheets comprising a pair of transversely spaced companion belt reaches trained to run side by side with their conveyer faces directed upward; sheet 45 guiding and retaining means overlying and extending along said belt reaches and opposed to their conveyer faces to hold an interposed sheet disposed between both belts and the guiding and retaining means with a medial portion of the 50 sheet bridging the space between the belt reaches; supporting means engaging the under faces of said belt reaches and supporting them in co-operative relation to said sheet retaining means; and means to flex said medial portion of the sheet 55 out of the plane of the belt reaches.

24. In a drag belt conveyer line for conveying sheets, a conveyer belt; a frame structure for supporting the line including longitudinal rods extending along the line; a transverse bar detachably fixed to said frame rods and removable from said rods transversely thereof; sheet guiding and retaining means supported by said transverse bar and forming a track extending along said belt to hold sheets thereto for conveyance; and means carried by said transverse bar to adjust said sheet retaining means into close uniform cooperative contact with the belt. 60 65

25. In a drag belt conveyer line for conveying sheets, a pair of transversely spaced companion 70 conveyer belts trained to run side by side; sheet guiding and retaining means extending along said belts to hold a sheet to both belts for conveyance thereby with a medial portion of the sheet bridging the space between the belts; means extending 75

- along the belts to hold said medial portion of the sheet flexed out of the plane of the belts; and means to drive both belts in the same direction and at the same speed.
26. In a drag belt conveyer line for conveying sheets, a pair of transversely spaced, companion conveyer belts trained to run side by side; stationary sheet guiding and retaining means forming a track extending along said belts to hold an interposed sheet to both belts for conveyance thereby; and means to drive both belts in the same direction and at the same speed.
27. In a belt conveyer system having a skeleton supporting frame structure including a plurality of transversely spaced longitudinal rods arranged to define the frame, transverse frame-stiffening and shaft-supporting bars at opposite sides of said frame and having spaced hook-like portions opening inwardly of the frame and hooked around said frame rods, set screws carried by said transverse bars to releasably lock said hook-like portions to the frame rods, said transverse bars having shaft-receiving sockets, a pulley shaft extending transversely of the frame rods and supported in said sockets at opposite sides of the frame, and means releasably locking said shaft in the sockets to cooperate with the transverse bars to stiffen the frame, the transverse bars being outwardly removable from the frame transversely of the longitudinal rods upon release of said set screws and said shaft-locking means.
28. In a belt conveyer system having a skeleton supporting frame structure including a plurality of transversely spaced longitudinal rods arranged to define the frame, transverse frame-stiffening and shaft-supporting bars at opposite sides of said frame and having spaced hook-like portions hooked around said frame rods, means to releasably lock said hook-like portions to the frame rods, said transverse bars having shaft-receiving sockets, and a pulley shaft extending transversely of the frame rods and supported in said sockets at opposite sides of the frame.
29. In a belt conveyer system having a skeleton supporting frame structure including a plurality of transversely spaced longitudinal rods, a transverse frame-stiffening and shaft-supporting bar extending between said rods and having spaced hook-like portions opening transversely of the bar and hooked around said frame rods, set screws carried by said bar to releasably lock said hook-like portions to the frame rods, said transverse bar having a shaft-receiving socket, a pulley shaft supported in said socket, and means to releasably lock said shaft in the socket.
30. In a belt conveyer system having a skeleton supporting frame structure including a plurality of transversely spaced longitudinal rods, a transverse frame-stiffening and shaft-supporting bar having spaced hook-like portions opening transversely of the bar and hooked around said frame rods, means carried by said bar to releasably lock said hook-like portions to the frame rods, said transverse bar having a shaft-receiving socket, and a pulley shaft supported in said socket.
31. In a drag belt conveyer system for conveying sheets, a conveyer belt, stationary sheet guiding and retaining means in the form of a flexible track extending along said belt to hold sheets thereto for drag conveyance along the track, means to rigidly support said track at longitudinally spaced points, and adjustable means to bow the flexible track between said points to position and hold the track in cooperative engagement with the belt.
32. A drag belt sheet conveyer line comprising drag belt conveyer means having a pair of longitudinal, transversely spaced, companion sheet-engaging conveyer portions extending along the line side by side; sheet guiding and retaining means extending along the line to hold a sheet to both of said transversely spaced belt conveyer portions for conveyance thereby with an intermediate portion of the sheet bridging the space between said belt conveyer portions; and a ridge extending along the line and projecting between said belt conveyer portions to hold said medial portion of the sheet flexed between said belt conveyer portions.
33. A drag belt sheet conveyer line comprising drag belt conveyer means having a pair of longitudinal, transversely spaced, companion sheet-engaging conveyer portions extending along the line side by side; sheet guiding and retaining means extending along the line to hold a sheet to both of said transversely spaced belt conveyer portions for conveyance with an intermediate portion of the sheet bridging the space between said belt conveyer portions; and sheet-flexing means extending along the line and projecting between said belt conveyer portions to hold said medial portion of the sheet flexed between said belt conveyer portions.
34. A sheet conveyer line comprising a pair of companion sheet-engaging conveyer members spaced apart transversely of the line; sheet guiding and retaining means extending along the line to hold a sheet to both of said transversely spaced conveyer members for conveyance with an intermediate portion of the sheet bridging the space between said conveyer members; and sheet-flexing means projecting between said conveyer members to flex said medial portion of the sheet between said members.
35. A drag belt sheet conveyer line comprising drag belt conveyer means having a pair of longitudinal, transversely spaced, companion sheet-engaging conveyer portions extending along the line side by side; sheet guiding and retaining means extending along the line to hold a sheet to both of said transversely spaced belt conveyer portions for conveyance with an intermediate portion of the sheet bridging the space between said belt conveyer portions; and sheet-flexing means extending along the line and projecting between said belt conveyer portions to hold said medial portion of the sheet flexed between said belt conveyer portions, the sheet guiding and retaining means forming tracks for the sheet along opposite sides of said sheet flexing means and having lateral clearance along the outer longitudinal sides of the tracks for lateral entry to clean the tracks.
36. A drag belt sheet conveyer line comprising drag belt conveyer means extending along the line, and sheet guiding and retaining means forming a track extending along the line to hold an interposed sheet to said belt means for conveyance and having lateral clearance along a longitudinal edge of the track for lateral entry to clean the track; and means spaced transversely from said longitudinal edge to flex the sheet and hold it against displacement across the track as it is conveyed.
37. A sheet conveyer line comprising cooperating belt conveyer means and track means both extending along the line and disposed in opposed relation for conveyance of an interposed sheet along the track means by the belt means, and a sheet-flexing ridge borne by one of said means,

extending along the line and located at an intermediate position with respect to the width of the belt means and the track means to hold the medial portion of the sheet flexed as the sheet is conveyed, for the purpose set forth, the other of said cooperating means having medial clearance therealong to receive said ridge. 5

38. A sheet conveyer line comprising cooperating belt conveyer means and track means both ex-

tending along the line and in opposed relation for conveyance of an interposed sheet along the track means by the belt conveyer means, and sheet-flexing means in an intermediate position with respect to the width of said cooperating belt conveyer means and said track means to hold the medial portion of the sheet flexed as it is conveyed along the line, for the purpose set forth. 5
